(57) **CLAIM**

I claim the ornamental design for the nail and cuticle clippers, as shown.

DESCRIPTION

FIG. 1 is a perspective view of the nail and cuticle clippers. FIG. 2 is a side view of the nail and cuticle clippers; and, FIG. 3 is a plan view of the nail and cuticle clippers.

As illustrated by the above-referenced figures, the present invention is characterized by a main structure 1 formed by two portions 2 joined by a center point 3, where a joint pin 4 is found.

Each of the two portions 2 is formed by a front region 5 where the cutting edges 6 are located.

Each of the two portions 2 is formed in gripping sections 7, which present an insert 8 produced in a material different from the remaining structure of the pliers. The inserts 8 can receive engraving of a manufacturer's brand.

Gripping sections 7, from the central articulation region of the pliers, progressively increase in thickness, culminating in smooth terminations 9.
